(57) **CLAIM**

The ornamental design for a battery powered skateboard, as shown and described.

DESCRIPTION

FIG. 1 is a top, front, and right-side perspective view showing the battery powered skateboard;
FIG. 2 is a bottom, rear, and left-side perspective view thereof;

FIG. 3 is a right-side view thereof;
FIG. 4 is a left-side view thereof;
FIG. 5 is a front view thereof;
FIG. 6 is a rear view thereof;
FIG. 7 is top view thereof; and,
FIG. 8 is a bottom view thereof.

The broken lines in FIGS. 1 through 8 illustrate portions of the battery powered skateboard that are not part of the claimed design.
